UNITED STATES PATENT OFFICE.

JOHN B. BASKERVILLE, OF ROANOKE, VIRGINIA.

IMPACT RECORDER.

Application filed July 20, 1925. Serial No. 44,824.

To all whom it may concern:

Be it known that I, JOHN B. BASKERVILLE, a citizen of the United States, residing at Roanoke, in the county of Roanoke and 5 State of Virginia, have invented certain new and useful Improvements in Impact Recorders, of which the following is a specification.

The present invention consists of an impact recorder adapted to make a record of impacts sustained by railway rolling stock when in transit especially such impacts as are due to acceleration or deceleration.

Objects of the invention are to provide 10 impact recording mechanism of the above mentioned character in which one part of the mechanism is movable in correspondence to the movement of rolling stock but functions to effect a visible record only when the 15 impact is of predetermined intensity; to provide a marker carrying shaft operable by clock mechanism to progressively feed the marker in harmony with the movements of said mechanism; to provide a marker or 20 impression maker which, although constantly movable in response to the movements of the clock mechanism, is not permitted to function unless impacts of predetermined 25 intensity are sustained by the rolling stock; to provide a record sheet carrier normally held in a predetermined position 30 from which position it is displaced by the vibratory action of the rolling stock and urged into the zone of the marker or impression maker when the impacts imparted to 35 the rolling stock are severe.

A co-ordinate object of the invention is to provide a compact structure which operates with precision to make a record of impacts 40 sustained by a railway car or other supporting structure in transit which carries the recorder, to translate the intensity of the impacts and record the time of their occurrence.

While the above objects are construed to 45 be the principal objects of the invention at the present time, I am nevertheless aware that other objects of the invention will be apparent from my co-pending applications, Serial Number 756,668, filed December 18, 50 1924, and Serial Number 33,629, filed May 29, 1925, and also from the following speci-

fication and accompanying drawings in which latter:—

Fig. 1 is a top plan view of an impact recorder constructed in accordance with the 55 present invention and showing the lid of the recorder casing removed;

Fig. 2 is a vertical transverse sectional view of the recording mechanism in its 60 entirety;

Fig. 3 is a vertical longitudinal sectional view of the same;

Fig. 4 is a plan view of the manifold record sheets used with the present recorder;

Fig. 5 is a detail fragmentary perspective 65 view of one of the record sheet clamps;

Fig. 6 is a detail fragmentary sectional view of the impression maker or stylus used in the present invention;

Fig. 7 is a detail fragmentary side elevational view of a part of the pendulum carrying structure showing the manner of mounting the pendulum thereon and illustrating how this structure coacts with the presser bar; and

Fig. 8 is a detail fragmentary elevational view of one of the abutments and a part of the yoke illustrating their manner of engagement.

In the present invention I prefer to employ a casing or housing generally designated 8 which may be of the construction shown in the drawings comprising a body 9 having a hinged lid or closure 10. Suitable means, such as that indicated at 11, may be 80 employed for locking the lid from being casually opened and also if desired a handle 12 may be mounted on the top of the lid to facilitate carrying this device.

The recorder per se consists of a frame 90 embodying a base 13 which is detachably mounted on the bottom of the casing 8 and has extended upwardly from the lateral margins thereof a pair of parallel plates 14, preferably made of metal, one of which is 95 extended above the other, as indicated at 15.

Mounted between the plates 14 is a platen or record sheet carrier 16 which, in the present instance, consists of the segment of a cylinder and is rotatably mounted upon a 100 shaft 17 the ends of which latter are fixedly mounted in the plates 14. The ends of the

platen are spaced from the inner faces of the plates 14 by sleeves 18 which are journaled on the shaft 17. The platen is hollow and is equipped with a detachable rod 19 extending longitudinally therethrough which serves in the dual capacity of supporting counterbalancing mechanism for the platen, generally designated 20, and securing abutments 21 to the ends of the platen. The counterbalance mechanism, in the present instance, is shown as composed of a pair of strips 22 through which both the shaft 17 and rod 19 extend, the strips being secured, approximately midway their ends, by a brace 23 which spans the strips and serves as a support for the upper end of a spring 24. The spring 24 is of helical construction having the terminal of its upper convolution engaged through the eye of a bolt 25 the latter extending through the brace 23 and being equipped with a nut 26. The lower end of the spring is anchored on the base 13 of the frame, as indicated at 27. Weights or pendulums 28 complete the counterbalance mechanism one of each of these being detachably mounted on the inner face and at the lower end of each strip 22. The counterweight mechanism holds the platen in a predetermined position until it sustains an impact at which instant the platen moves in correspondence to the extent of movement of the counterweights. Movement is limited, however, by the spring 24 which is of predetermined resistance and the tension of which may be adjusted by movement of the nut 25.

The abutments 21 are shown to be rotatably mounted on the rod 19 and have their peripheries disposed to extend appreciably above the outer periphery of the platen. The abutments are adapted for engagement with a floatingly mounted yoke 29. The yoke is mounted within an oblong frame 30 one end of which latter is secured to one of the plates 14 while the opposite end is secured to the opposite plate and its extension 15. The free ends of the yoke extend through complementary openings formed in the base of the frame 30, the terminals of said yoke being bent at right angles to provide feet 31 which are normally in surface contact with the abutments 21. The top of the yoke 29 carries a pair of pins 32 the latter extending through corresponding openings formed in the top of the frame 30.

The yoke 29 is yieldingly engaged with the abutments 21 by means of a flat spring 33 which latter is clamped, midway its ends, to a saddle 34, the latter, in conjunction with the spring, being detachably engaged with the top of the frame 30. The free ends of the spring impinge against the free ends of the pins 32 to normally force the latter downwardly and thereby correspondingly move the yoke 29.

A time operated shaft 35 is employed one end of which passes through the extended portion 15 of one of the plates 14 and engages clock mechanism 36 which is mounted on the outer face of said extension 15. The shaft 35 extends through elongated openings 37 formed in the opposite ends of the yoke 29 and has its free terminal pointed, as indicated at 38, the latter being mounted in a complementary socket formed in the shank of a screw 39. The screw 39 is detachably engaged in the outer end of the frame 30. By providing elongated slots 37 it is apparent that the yoke 29 may move up and down without interference by the shaft 35. The shaft 35 is rotated by the clock mechanism at any predetermined velocity and has adjustably mounted thereon marker means generally designated 40. The marker means, in the present instance, consists of a movable stylus carrier 41 of U-shaped configuration, the stylus, designated 42, being fixedly carried by the vertex of the U and embodying a roller 43 for impingement against a record sheet 44 mounted upon the platen 16 in a manner more fully hereinafter described. By providing the roller 43, frictional resistance is reduced to a minimum. The carrier 41 slides through a nut 45 screwthreaded upon the shaft 35 and is normally urged upwardly, in order to keep the roller 43 out of contact with the record sheet 44 by a spring 46 which latter has one end in engagement with the nut 45 and the opposite end engaged with a fixed nut 47. The tension nut 47 is fixedly engaged with the stylus carrier 41 and has a bolt 48 threaded therein. Movement of the bolt adjusts the distance between the bolt head and the yoke 29. The stylus extends through a longitudinal slot 49 formed in the bottom of the frame 30. Consequently, the marker means is permitted to move longitudinally on the shaft 35 but is prevented from rotary movement. Since the stylus is normally held in spaced relation to the platen and record sheet carried thereby and is not capable of lateral or rotary motion, it is apparent that any impression upon the sheet 44 must be made by movement of the platen which will urge the record sheet into the zone of the stylus.

The platen 16 is normally held in an inoperative position by suitable locking mechanism comprising a bed plate 50 and a presser bar 51. The bed plate consists of a metal strip detachably secured on the top of the base 13 the ends thereof being bent upwardly at right angles and pivotally connected to the sides of the presser bar. The upper margin of each side of the presser bar 51 is provided with an intermediate arcuate depression 52 which is intersected by a slot 53, as advantageously illustrated in Fig. 7 of the drawings. Each of the slots 53 com-

plements and is adapted to receive an angle lug 54. The lugs 54 are fixedly secured to the outer faces of the strips 22 near the lower terminals of the latter. The forward end 5 of the presser bar is twisted, as shown at 55, so that its lower face parallels the upper face of the base 13 for engagement with a coil spring 56 which latter is interposed between the part 55 of the frame and the base 13 as illustrated in Fig. 3 of the drawings. The expansive action of the spring 56 normally forces the presser bar upwardly in order to retain the lugs 54 in the recesses 53. When it is desired to permit the platen to 10 operate, the presser bar may be depressed downwardly and secured in the depressed position by suitable means. The means employed for this purpose in the present instance consists of a locking bolt 57 the lower 15 end of which is screwthreaded to engage an internally screwthreaded sleeve 58 mounted in the base 13. Upward movement of the presser bar on the bolt is limited by an annulus 59 formed on the bolt and positioned 20 above the presser bar. Consequently, when the bolt 57 is urged downwardly and screwthreaded into the sleeve 58, the presser bar 51 is correspondingly moved downwardly 25 against the resistance of the spring 56 and 30 the lugs 54 freed from their slots 53. Consequently, the platen is free to move since the lugs are permitted to oscillate above the arcuate depressions 52 clear of the presser bar. When the bolt is disengaged the presser 35 bar is urged upwardly by the expansive action of the spring 56 and the lugs 54 guided into the slots 53 due to the arcuate formation of the depressions 52.

In order to make a visible record of the 40 oscillations of the platen and thereby translate the movements of the rolling stock, especially as caused by acceleration and deceleration, manifold record sheets 60 are provided which may be of any desired construction and are shown herein to illustrate the application of the invention. The record sheets are provided with openings 61 adjacent one end which are eccentric to a straight line drawn transversely across the 45 sheet for engagement with staggered studs 62 which are mounted on the periphery of the platen 16. By arranging the studs and openings of the record sheet in this manner it is necessary that the record sheet be placed 50 on the platen in a predetermined position to avoid possibility of error. The sheets are clamped from displacement by suitable brackets 63. Each bracket consists of a substantially U-shape structure the terminals 55 of which are pivotally engaged with the ends of the platen and are swingable into position below the lateral margins of the platen for clamping the record sheet from displacement. One of the marginal edges of each 60 bracket is reversely folded upon itself to

provide a yielding flange 64 which engages the record sheet. Consequently, the record sheet is yieldingly held on the platen without mutilating the record sheet and positively preventing its accidental displacement. 70

In use of this device the record sheets are first clamped on the platen 16 in the manner above described and the entire recorder, which is still in a normally locked position, 75 placed in a car of the railway rolling stock or mounted on any other support of which the impacts sustained thereby are to be recorded. After being so positioned the locking bolt 57 is threaded into the sleeve 58 80 thereby depressing the presser bar 51 in a manner hereinbefore described. Movement of the rolling stock will correspondingly impart an oscillatory motion to the platen 16 in an obvious manner. Since, however, 85 the impression maker is clear of the record sheet mounted on the platen, no record will be made of the vibrations of the rolling stock or other support so long as these vibrations or impacts are normal or do not exceed a 90 predetermined degree of intensity. When, however, the impacts do exceed this predetermined degree of intensity the platen will be rocked against the resistance of the spring 24 to a point where the abutments 21 95 no longer impinge against the feet of the floating yoke 29 thereby permitting the yoke to move downwardly in its entirety under influence of the spring 33 and engage the head of the bolt 48. This action depresses 100 the stylus carrier 41 against the resistance of the spring 46 and brings the wheel 43 into contact with the record sheet 60. The oscillations of the platen while displaced, as 105 above set forth, will be indicated on the record sheet and the severity of the impact determined by the extent of the stroke on the record sheet caused when the wheel 43 comes in contact therewith. Furthermore, since the shaft 35 is then operated, and the stylus 110 or marker moved in correspondence to the rotation of the shaft, the time of the occurrence of the impact will be apparent from the location of the strokes or marks on the record sheet. After the force of the impact 115 has been spent and the traction of the rolling stock returned to normal, the platen will correspondingly return to its neutral zone under the contractile action of the spring 24. When the rolling stock which carries 120 the recorder reaches its destination the platen is again locked by disengaging the bolt 57 and the record sheets removed by disengaging the clamping brackets 63 in a manifest manner. 125

I am, of course, aware that numerous changes in the details of construction, proportion and arrangement of parts will suggest themselves to anyone skilled in the art 130 after consideration of my specifications and

drawings since I have attempted to herein set forth only one preferred structure for carrying out the principle of this invention. I, therefore, reserve the right to make such changes in the details of construction, proportion and arrangement of parts as come within the scope of the present claims.

What is claimed is:—

1. An impact recorder for railway rolling stock including mechanism carried by the rolling stock and embodying a movable record sheet holder and a time operated marker, the record sheet impinging against the marker when impacts of predetermined 10 intensity are sustained by the rolling stock.
2. An impact recorder for railway rolling stock including mechanism carried by the rolling stock and embodying a record sheet holder movable by the accelerations 20 and decelerations of the rolling stock, and a marker to impinge against the holder when the latter moves to a predetermined extent.
3. An impact recorder for a moving mass including a record sheet holder carried by 25 the mass but movable independently of the latter while the mass is in motion, a marker for engagement with the holder when the latter moves a predetermined distance, and a clock mechanism operatively connected to the marker for moving the latter across the sheet holder.
4. An impact recorder for a moving mass including a record sheet holder secured to the mass but movable independently of the 30 latter when the mass is in motion, a marker arranged to lie in proximity to said holder but engageable therewith only when the holder moves to a predetermined extent, a clock mechanism to feed the marker across the record sheet holder to fix the time of occurrence of impingement of the marker with the holder, and means to normally 35 secure the holder from movement in the absence of an appreciable impact sustained by the mass.
5. An impact recorder for railway rolling stock including recording mechanism carried by the rolling stock and embodying a movable record sheet holder and a marker 40 engageable with the holder only when the latter moves into a predetermined zone.
6. An impact recorder for railway rolling stock including recording mechanism embodying a rotatable screw shaft with a marker mounted thereon, said mechanism 45 also embodying a record sheet holder automatically movable by the rolling stock vibrations to bring the marker into engagement with the record sheet when the latter moves into a predetermined zone. 50
7. An impact recorder for rolling stock including recording mechanism embodying a clock operated shaft equipped with a marker automatically movable by rotation of the latter, and a record sheet holder for 55 engagement with the marker when the rolling stock sustains impacts of predetermined intensity and impacts exceeding a predetermined intensity. 60
8. An impact recorder including a movable record sheet carrying platen, and a stylus automatically movable into contact with the platen when the latter moves into a predetermined position. 70
9. An impact recorder including mechanism embodying a movable record sheet carrying platen and a stylus contacting with the platen and engageable therewith when the platen reaches a predetermined position, and means cooperable with the stylus for 75 adjusting the point at which the platen is effective to urge the stylus into engagement therewith. 80
10. An impact recorder having a marking element constantly driven by a clock 85 mechanism, a movable platen engageable with the marking element when the platen moves a predetermined extent, and means to lock the platen from movement. 90
11. An impact recorder for railway rolling stock including mechanism carried by the rolling stock and embodying a record sheet holder, and a marker engageable with the sheet, when excessive impacts are sustained, and movable on the sheet until the 95 force of the impact has been spent. 95

JOHN B. BASKERVILLE.
